UNITED STATES PATENT OFFICE.

MAURICE D. K. BREMNER, OF CHICAGO, ILLINOIS.

TABLE PAD.

Application filed March 14, 1927. Serial No. 175,157.

My invention relates to table covers and the like, being more particularly concerned with the provision of a table pad consisting of a plurality of quick detachable parts, 5 which may be assembled to form pads of various sizes and shapes.

One of the objects of my invention is the provision of a table pad of the class described, having a plurality of separable pads 10 of various shapes and sizes which are joined together by a plurality of quick detachable connectors, disposed and protected in such manner as to form a pad of substantially smooth and even thickness.

15 Another object of my invention is the provision of a novel quick detachable connector for the purpose set forth, consisting of a pair of thin flat complementary members, which are simple in structure and easy 20 to manufacture, which are adapted to hold the component parts of the pad firmly together to prevent relative sliding, and which accomplish this result without forming thick spots or projections on the table pad.

25 Other objects and advantages of my invention will appear more fully from the following description, and from the accompanying drawings, in which

Figure 1 is a plan view of the preferred 30 embodiment of my table pads;

Figure 2 is a plan view of a modified form for round tables.

Figure 3 is a plan view of a portion of a 35 table pad showing a modified form of my invention.

Figure 4 is a cross sectional view of a portion of my table pad showing the connectors, taken on the line 2—2 of Figure 3.

Figure 5 is an enlarged detail view of the 40 connectors with the covering for the connectors removed.

Referring to Figure 1, 10 indicates a section of the table pad, preferably rectangular in form, which is adapted to cover a substantially rectangular portion of a table top, 45 and if desired the size of this section may be made such that two of such sections are required to cover the table top in its folded position. When it is desired to add leaves

to the table top, a plurality of smaller sections 11 and 12 may be provided for the purpose of adding to the sections 10 to cover the central portion of the table and it will be observed that my table pad is thus made adjustable to cover tables of any length. 50 Referring to Figure 2, I have here shown a modified form of table pad, for circular table tops, comprising two semicircular sections 13 removably held together. The sections 10 may also be provided with connectors 15 and 17 at the outer edge if desired and the end sections 13 added thereto to make a pad capable of covering a table with hinged end pieces. It will be understood that though the end sections 13 are 55 shown substantially semicircular in form, that the shape of these sections may be varied to correspond to the shape of the end pieces of the table, whether it be rectangular, rectangular with rounded corners, or other 60 irregular shapes.

In order to assemble the sections 10, 11 and 12, shown in Figure 1, together with counterparts of these sections to cover the other end of the table, I provide a plurality 75 of small flat connectors, which are affixed to the respective table pad sections to provide a quick detachable connection capable of holding these sections together.

The connectors employed for this purpose 80 consist of a female connector and a male connector, adapted to be received in the same, and in order that the separate table pad sections may be interchangeable the male and female connectors are preferably 85 disposed as shown in Figures 1, 2 and 3 with male and female connectors inversely mounted upon the same ends of the table pad sections.

Thus, it will be observed that on the end 90 pad section 13, the upper connector 14 is a male connector adapted to be received in the female connector 15, while on the lower portion of the section 13 there is mounted a female connector 16 adapted to connect 95 with the male connector 17 upon the pad section 10. It will thus be observed that if two identical end sections 13 are em-

ployed together, that the female connector 16 of one section will be adapted to connect with the male connector 14 of the other section, and that both connectors will be so located as to fit one another. In a similar manner the connectors on the other end of the pad section 10 are inversely located, the upper connector 18 being a male connector, while the lower connector 19 is a female connector, and it will be observed that either end of the pad section 10 will connect with the end section 13 when the connectors are thus arranged. The connectors upon the middle sections 11 and 12 are likewise inversely arranged for the same purpose, the connectors 20, 21, 22 and 23 being male connectors, while the connectors 24, 25, 26 and 27 are female connectors. The balance of the table pad (not shown) which may be similar to that shown in Figure 3 is likewise equipped with connectors.

Referring to Figure 4, 28 indicates the body portion of my table pad, which may consist of a layer of cotton or wool felt cut to the conformations shown in Figure 3, and covered upon one side by a layer 29 of fabric which is preferably a closely woven flannel, and upon the other side by a layer of closely woven fabric 30 which is covered with rubber on its exterior surface, as at 31. In order that the table pad may serve a variety of purposes, the flannel covering 29 is preferably of a dark green color, adapted to be restful to the eyes, and my table pad is therefore adapted to be used in its reversed position as shown in Figure 2 for furnishing a card playing surface. The rubber surface 31 is preferably pure white in color, in order to furnish a white background for table cloths or other coverings employed upon the table pad.

In order to secure the bodies of the pad sections and their respective coverings firmly together, and to provide a pad of maximum flexibility, along diagonal lines, I prefer to fasten these parts together with a plurality of regularly spaced lines of diagonal stitching, the lines of stitching being alternately oblique in opposite directions, extending across the pad as shown in Figure 1. As the needles employed in forming these lines of stitching would ordinarily produce a great number of apertures in the rubberized fabric 31, thereby rendering its waterproofing qualities ineffective, I prefer to assemble the flannel covering 29, the body 28, and upper fabric 30 first by stitching these parts along the lines shown in Figure 1, after which the surface 31 of the fabric 30 may be covered with rubber as shown.

The rubber coating 31 may consist of a thin sheet of white rubber which is affixed to the fabric 30 by a layer of ordinary rubber cement. The whole pad may then be passed

through heated pressure rolls, firmly pressing and vulcanizing the rubber and fabric together.

The rubber coating 31, therefore, not only covers and renders impervious the fabric 30, but it completely covers the apertures formed by the lines of stitching 32, the only external evidence of these lines of stitching upon the rubber layer being the presence of a plurality of lines of inward creases corresponding to the location of the lines of stitching 32. It will thus be observed that the rubber covered fabric 31 forms an upper covering for the table pad, which is impervious to moisture, and which is adapted to protect both the interior of the pad and the table top upon which it lies.

After the main portion of the pad sections have been constructed as described, the edges of the same are bound together by a binding tape 33, preferably a narrow strip of closely woven white fabric having its woof and warp diagonal to its length, and likewise covered with an exterior layer of white rubber. The tape is folded about the edge of the pad, both edges of the tape being turned under also, and stitched to the pad by a single line of stitching 34 passing through the upper edge (Fig. 2) of the binding tape 33, the flannel fabric 29, the felt body 28, the fabric 30 and rubber 31, and the lower edge of the binding tape 33. The binding tape 33 extends completely about the periphery of each pad section, the ends of the tape being slightly overlapped and thus all raw edges of fabric are protected and covered to form a finished pad. The biased binding tape greatly adds to the flexibility of the edge of the pad due to the direction of its woof and warp, and at the same time adequately protects these edges against unraveling. At the same time all parts of the white side of the pad may be washed with a wet rag as it is completely covered with rubber.

I shall now describe in detail the connector which is preferably employed with my table pad sections to hold these parts together without forming any substantially thick spots or projections upon the table pad itself.

Referring to Figure 5, 35 and 36 indicate two enlarged portions of any pad section which have been brought into abutting relation and which are provided with the female connector 37 and the male connector 38. The female connector 37 comprises a thin flat piece of metal plate, which may be of steel or other resilient metal, but which I prefer to construct of ordinary tin, which possesses sufficient resilience for the purpose desired.

The female connector 37 is formed of a substantially rectangular piece of metal having an outwardly projecting tab 39 for

the purpose of fixing the connector upon the pad. The ends of this rectangular major portion may be bent under at points along the outline of the tab 39 so that the edges 5 40 and 41 of the metal plate are brought into abutting relation to form an open tube of substantially rectangular cross section which is adapted to receive the end 42 of the male connector 38. In order to facilitate 10 the insertion of the male connector, the adjacent ends 43 and 44 of the folded portions of the female connector are preferably slightly extended, as shown at 45, in Figure 4, thereby forming a shoulder upon 15 which the male connector may be easily located for insertion into the female connector 37. The female connector 37 may be firmly fixed to the pad section by means of a tubular rivet 46 having a flat round head 20 47, and if the pad section is firmly clamped between the head 47 and the connector 37 by the rivet 46, these parts may be fixed together without substantially increasing the thickness of the pad at this point. 25

The male connector 38 comprises a flat piece of metal similar to that used in the female connector 37, having a similar tab 39 with an aperture 48, which is adapted to receive a similar rivet 46 to affix the connector to the pad section. The male connector 38 is provided with an outwardly extending tongue 49 slightly narrower than the tab 39, thereby forming the shoulders 50 which are adapted to limit the extent of 35 the insertion of the tongue 49 into the connector 37. The size of the tube in the female connector 37 may be made such that the folds 40 and 41 slightly clamp the tongue 49, but I prefer to form the aperture in the female connector slightly larger than the tongue 49, providing the tongue 49 with a plurality of transverse bends or crimps as at 51 and 52, forming ridges or points of contact upon the tongue 49, which 45 are adapted to cooperate with the interior of the connector 37 to frictionally hold these parts together. The transverse crimps 51 and 52 give the male connector increased resilience and permit a firm connection between these parts, with a considerable variation in the size of the aperture in the female connector. The male connector 38 is likewise affixed to the table pad sections 50 after the manner described for the female connector, and this male connector presents even less possibility of points of increased thickness or protrusion upon the pad.

As the flannel covering 29, upon which side the connectors are disposed, is generally in contact with the table, the major portions of the connectors 37 and 38, together with their rivets, are covered by small tabs of flannel 53 of substantially the same shape as that portion of the outline 65 of the connectors which lies upon the pad,

but slightly larger than the connectors, so that the tabs 53 may be fixed upon the connectors by a line of stitching 54 passing around the exterior edge of the connectors and extending through the pad section. 70

While the stitching 54 produces a line of perforations in the rubber layer these perforations are so near the edge that their presence is immaterial, but if desired, the connectors and tabs 53 might be affixed before 75 the rubber layer is added, thereby avoiding all perforations. The rivets 46 are preferably tinned or nickelized to present a non-corroding surface, and the heads 47 may clamp the pad slightly so that they are disposed in a slight depression in such manner that the heads do not actually come in contact with the table when that side of the pad is against the table top. 80

It will thus be observed that I have invented a table pad consisting of a plurality of separable sections which are joined together by an extremely flat and simple form of connector, and which table pad is adapted both to be used as a protective covering 85 underneath the usual table cloth or as a card playing surface for tables of all types. By means of the form of diagonal stitching shown, the flexibility of my pad is greatly increased, being adapted to extend over the 90 edges of the table and to readily fold down on each side of a corner along the lines of flexure formed by the diagonal stitching. 95

While I have shown and described the preferred embodiment of my invention, many modifications may be made without departing from the spirit of the invention, and I do not wish to be limited to the precise details of construction set forth, but desire to avail myself of all changes within 105 the scope of the appended claims.

Having thus described my invention, what I claim as new and desire to secure by Letters Patent of the United States, is:

1. In a table pad, the combination of a 110 plurality of pad sections of various sizes and shapes adapted to be combined to cover an extensible table top, with a plurality of connectors comprising a female member consisting of a flat piece of metal of substantially rectangular shape, with opposite sides bent into abutting relation to form a tube-like member, and a flat male member comprising a flat metal plate adapted to fit within said tube-like member, and means for 115 attaching said connectors to said pad sections, said connectors being depressed in the surface of said sections to prevent contact of the connectors with the table.

2. In a table pad, the combination of a 125 plurality of pad sections of various sizes and shapes adapted to be combined to cover an extensible table top, with a plurality of connectors comprising a female member consisting of a flat piece of metal of substan- 130

tially rectangular shape, with opposite sides bent into abutting relation to form a tube-like member, having a plurality of resilient transverse corrugations; a projecting flange on one side of the open end of said female member, and means for attaching said connectors to said pad sections, said connectors

being depressed in the surface of said sections to prevent contact of the connectors with the table.

In witness whereof, I hereunto subscribe my name this 8th day of March, 1927.

MAURICE D. K. BREMNER.
